F. E. BEST

PADLOCK

Filed Dec. 6, 1923

Frank Ellis Best.
INVENTOR

UNITED STATES PATENT OFFICE.

FRANK ELLISON BEST, OF SEATTLE, WASHINGTON, ASSIGNOR TO FRANK E. BEST, INC., OF SEATTLE, WASHINGTON, A CORPORATION OF WASHINGTON.

PADLOCK.

Application filed December 6, 1923. Serial No. 678,909.

To all whom it may concern:

Be it known that I, FRANK ELLISON BEST, a citizen of the United States, residing at Seattle, in the county of King and State of Washington, have invented a new and useful Padlock, of which the following is a specification.

My invention relates to improvements in padlocks and is in the nature of an improvement on the padlock shown and described in my Patent No. 1,479,214 issued January 1, 1924.

An object of my invention is to improve and simplify the construction of padlocks of this nature and to render the same more secure and more reliable and efficient in operation.

A more specific object is to provide a padlock having a J-shaped shackle whose longer leg is slidably and rotatably supported within the body of the lock in such a manner as to afford a bearing of maximum length the bottom end of said longer shackle leg being bored for the reception of a compression spring that urges the shackle outwardly.

Other and more specific objects will be apparent from the following description taken in connection with the accompanying drawings.

30 In the drawings Figure 1 is a view in longitudinal section substantially on broken line 1—1 of Fig. 3 of a padlock constructed in accordance with my invention showing certain parts in elevation and showing the shackle in an unlocked position.

Fig. 2 is a similar view substantially on broken line 2—2 of Fig. 4, showing the shackle in a locked position.

Fig. 3 is a view in cross section substantially on a broken line 3—3 of Fig. 1.

Figs. 4 and 5 are views in cross section respectively substantially on broken lines 4—4 and 5—5 of Fig. 2.

Fig. 6 is a detached view in perspective of a locking tumbler embodied in the invention.

Referring to the drawings, throughout which like reference numerals designate like parts, I show a padlock embodying a housing 7 of one piece construction having an integral top end 8 and recessed, as shown, by boring from the bottom end upwardly, three intersecting tubular bores 9, 10, and 11, said bores leaving inwardly projecting ridges 12 on the inner walls of the housing.

The top wall 8 of the housing is provided with two perforations 13 and 14 through which the two legs 15 and 16 of a shackle 17 are arranged to be inserted. The longer shackle leg 15 is adapted to fit within a bore 18 in a plug 19 that is arranged to be inserted from the bottom of the housing 7 into the recess 9 at one side thereof. The plug 19 is provided with a slot 20 extending from the top downwardly crosswise of the bore 18 and the longer shackle leg 15 is provided with a cross pin 21 movable in said slot, a counterbore being provided at the top of the bore 18 to permit the cross pin 21 to turn entirely around. The cross pin 21 limits the outward movement of the shackle 17, prevents turning of said shackle except when it is in its outermost position and prevents shackle 17 from being moved inwardly from the unlocked position except when it is properly aligned so that the shorter leg 16 of the same will enter the perforation 14.

After the plug 19 is inserted it may be permanently secured in the housing by riveting or clinching the metal of the housing 80 over the bottom edges of the plug.

The longer shackle leg 15 is adapted to extend substantially to the bottom of the plug 19 thereby affording within said plug a bearing of maximum length 85 and the bottom end of said shackle leg 15 is bored to form a recess 23 for receiving a compression spring 24 that exerts an upward pressure on the shackle leg. The lower end of the recess 23 in the shackle leg is flared as at 25 to preclude any possibility of pinching coils of the spring 24 between the bottom end of the shackle leg and the bottom of the bore 18 in the plug 19. The bore 18 in the plug 19 extends, as nearly as possible, to the bottom of said plug and the positioning of the spring 24 in the recess 23 in the bottom of the shackle leg 15 makes it possible to secure a bearing of maximum length of the shackle leg 15 in the plug 19 so that the shackle will be securely supported and will have no play even when in the unlocked position.

The shackle 17 is arranged to be locked in the housing 7 by a locking tumbler, Fig. 6, embodying a disc 26 having oppositely disposed locking members 27 arranged to lock into notches 28 and 29 in the shackle legs 15 and 16 respectively. The disc 26 is provided with centrally arranged bearing 110

stud 30 and 31 that are journaled in the top 8 of the housing and in a partition member 32 and said disc is provided with two slots 33 and 34 that register with corresponding slots in the partition member 32. A spring 35 is wound around the bearing stud 30 and arranged to urge the locking tumbler into locked position. The partition member 32 is provided with upwardly protruding end portions 36 that bear against the top 8 of the housing and said partition forms a compartment in which the locking tumbler operates.

The locking tumbler is arranged to be moved into an unlocked position by pin tumbler locking devices embodying a lock core 37 shaped to fit the housing 7 and arranged to be removably locked therein by a locking gate 38 adapted to lock into a groove 39 provided in one of the inwardly projecting ridges 12 in the interior of the housing, the movement of the gate 38 and removal of the core 37 from the housing being controlled by a second or upper shear line in the lock in a manner similar to that described in my Patent Number 1,384,022 issued July 5, 1921.

The lock core 37 is provided with a key plug 40 having on its inner end a disc 41 provided at points removed from the center with two pins 42 that extend through the slots in the partition member 32 and engage within the slots 33 and 34 in the locking tumbler. The slots 33 and 34 in the locking tumbler are long enough and are positioned so as to leave sufficient clearance for the pins 42 to be rotated through an angle of substantially fifteen degrees to the left from the position shown in Fig. 1 for the purpose of unlocking the core 37 from the housing 7 without moving the locking tumbler. When the lock is operated to unlock the locking tumbler from the shackle 17 the pins 42 are first moved idly to the left far enough to engage the ends of the slots 33 and 34 and are then moved further to turn the locking tumbler into the unlocked position shown in Fig. 3. As soon as the locking tumbler releases the shackle the spring 24 will snap the shackle outwardly into the position shown in Fig. 1 in which position the locking member 27 on one end of the locking tumbler will engage with the longer leg 15 of the shackle 17 and be held in an unlocked position (see Fig. 3) thus permitting the pins 42 to be moved in the slots 33 and 34 back into the position shown in Fig. 3 so that the tumbler pins 43 in the lock core 37 will be properly aligned and the key 44 with which the lock is operated may be withdrawn.

From the preceding description it will be seen that the slots 33 and 34 in the disc portion 26 of the locking tumbler function to permit the removal of the lock core 37 without turning the locking tumbler and to per-

mit the reverse turning movement of the key plug necessary in order to remove the key.

The lock core 37 preferably has a face plate 45 rigidly secured thereto and arranged to fit within a suitably counterbored portion 46 in the end of the lock housing.

In operation when the key 44 is inserted and the locking tumbler turned into the unlocked position, Fig. 3, the spring 24 will snap the shackle outwardly so that the shorter leg 16 of the same will clear the top of the padlock and said shackle may be turned sidewise and disengaged from any member to which it may be secured.

After the locking tumbler is unlocked the key 44 may be removed. The padlock may be again locked at any time by pushing the shackle 17 downwardly into the housing 7 until the notches 28 and 29 register with the locking member 27 and the spring 35 snaps such locking members 27 back into locked position.

The padlock is neat in appearance, compact in construction and makes possible the use of a pin tumbler lock core having a maximum number of tumbler barrels in a padlock of standard size.

The foregoing description and accompanying drawings clearly disclose one preferred embodiment of my invention but it will be understood that this disclosure is merely illustrative and that numerous changes may be made within the scope and spirit of the following claims:

I claim:

1. A padlock embodying a hollow housing having a closed top end and an open bottom end, a partition member disposed adjacent said top end and cooperating therewith to form a narrow chamber for the reception of latch mechanism, a plug member arranged to fit within said housing and to extend from the bottom end thereof to said partition, said plug having a bore extending downwardly to a point near its bottom end, a J-shaped shackle having its longer leg arranged to fit slidably within the bore in said plug, said shackle leg having a bearing that extends throughout substantially the entire length of said plug and a spring urging said shackle outwardly.

2. A padlock embodying a hollow housing, open at one end and closed at the other, a partition member adjacent said closed end to form a latch receiving chamber, a plug insertable from the open end of the housing and extending from said partition member to the open end of said housing, said plug having a bore extending from the end adjacent said partition substantially to the other end, a J-shaped shackle having a longer leg bored from the bottom upwardly and arranged to fit slidably within the bore in said plug and having therein a bearing of maximum length, a spring in the end of said

longer leg urging said shackle upwardly and means on said longer shackle leg for engaging said partition member to limit the upward movement of said shackle.

5 3. A padlock embodying a housing, a plug member arranged to fit within said housing, said plug member having a bore that extends from the top downwardly and having a slot extending from the top downwardly cross-

10 wise of said bore and having a counterbore at the top of said bore, a J-shaped shackle having its longer end rotatably and slidably disposed in said bore and a pin in said shackle movable in the slot and rotatable in

15 the counterbore in said plug.

4. A padlock embodying a housing, a J-shaped shackle having one leg rotatably and slidably supported in said housing said shackle having oppositely disposed tumbler

20 receiving notches, a pivotally mounted tumbler arranged to engage within said notches to lock said shackle said tumbler having slots provided therein, a key operated pin tumbler lock, and means on the end of said

25 lock for engaging within said slots to move said tumbler into unlocked position, said slots permitting reverse turning movement of said lock when said tumbler is in an unlocked position whereby the key may be

30 withdrawn from said lock.

5. In a padlock a housing, a J-shaped shackle having two legs supported in said housing and provided with tumbler receiving notches, a tumbler rotatably mounted

35 and having oppositely protruding members arranged to enter the notches in said shackle said tumbler also having slots, a key operated pin tumbler lock having a key plug provided on the end with eccentric pin means

40 arranged to enter the slots in said tumbler for operating the same, said slots affording sufficient clearance for said eccentric pin means to permit withdrawal of a key from said lock when said tumbler is in unlocked

45 position.

6. A padlock embodying a housing of one piece construction having an integral top end and an open bottom end and having an internal cavity formed by boring three inter-

50 secting holes that leave inwardly protruding segments therebetween a tubular plug member arranged to be inserted into one of said holes, a J-shaped shackle having a longer end arranged to fit slidably within said tu-

55 bular plug and affording a bearing of maximum length therein, the bottom end of said shackle leg having a tubular recess, a comp-

ression spring disposed within said tubular recess and locking means in said housing for

60 locking said shackle.

7. A padlock embodying a housing of one piece construction having an internal cavity leaving an open bottom end and a closed top end, a partition member arranged to be inserted in said housing said partition member having two oppositely disposed slots and having upwardly extending portions that abut against the end of said housing, a J-

25 shaped shackle having oppositely arranged tumbler receiving notches and having its longer leg rotatably and slidably supported in said housing, a locking tumbler mounted for oscillation between said partition and the end of said housing and having slots

70 that register with the slots in said partition, oppositely disposed locking members on said tumbler arranged to lock within the notches in said shackle, a pin tumbler lock arranged to be inserted in said housing and means on

75 the end of said lock arranged to project through said slots and operate said locking tumbler.

8. A padlock embodying a housing of one piece construction having an integral top end and an open bottom end and having an internal cavity formed by boring three intersecting holes that leave inwardly protruding segments therebetween, a partition member arranged to be inserted in said housing

80 said partition member having two oppositely disposed slots and having upwardly extending portions that abut against the end of said housing, a tumbler member mounted for oscillation between the end of said housing and said partition said tumbler member having oppositely disposed locking elements

85 and having slots, a plug member arranged to be inserted into one of the holes at one side of said housing said plug member having a tubular bore extending to a point near the bottom end thereof, a J-shaped shackle having a longer and a shorter leg each provided with a tumbler receiving notch, the longer leg fitting snugly within the bore in said

90 plug member and affording a bearing of maximum length therein and said longer shackle leg having a tubular bottom end, a compression spring disposed in said tubular bottom end, a lock core of substantially figure

95 eight cross sectional shape disposed in said housing, a key operated disc rotatable on the end of said lock core, two pins on said disc at points removed from the center and arranged to extend through the slots in said

100 partition and in said tumbler for turning said tumbler to release said shackle and a spring urging said tumbler into a locked

105 position.
